UNITED STATES PATENT OFFICE

99,167

DESIGN FOR A CREAM DIPPER

Charles S. McCarthy, Toledo, Ohio

Application December 30, 1935, Serial No. 60,339

Term of patent 7 years

To all whom it may concern:

Be it known that I, Charles S. McCarthy, a citizen of the United States and resident of Toledo, county of Lucas, State of Ohio, have invented a new, original, and ornamental Design for a Cream Dipper, of which the following is a specification, reference being had to the accompanying drawing, forming a part thereof.

Figure 1 is a side elevation of the cream dipper, showing my new design; and

Figure 2 is a bottom plan view of the cream dipper shown in Figure 1.

I claim:

The ornamental design for a cream dipper, substantially as shown.

In testimony whereof I have hereunto signed my name to this specification.

CHARLES S. McCARTHY.
